CLAIM

The ornamental design for an outdoor light, as shown and described.

DESCRIPTION

FIG. 1 is a first perspective view of an outdoor light showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of another state of the outdoor light thereof; and,

FIG. 10 is an enlarged view of the selected portion in FIG. 2.

The broken lines of alternating length are for the purpose of illustrating the boundaries of the enlarged fragment shown in FIG. 10 and form no part of the claimed design.

1 Claim, 10 Drawing Sheets(56)
